(57) **CLAIM**

The ornamental design for a clip device, as shown and described.

DESCRIPTION

FIG. 1 is a perspective view of a clip device showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is a perspective view thereof, the hands and the ring depicted by means of broken lines being for illustrative purposes only and forming no part of the claimed design, in which the ring may be attached onto the hands with the clip device.
